UNITED STATES PATENT OFFICE.

FRIEDRICH TWICK, OF SHEBOYGAN, WISCONSIN.

COMBINED LAND-ROLLER AND CLOD-CRUSHER.

SPECIFICATION forming part of Letters Patent No. 365,209, dated June 21, 1887.

Application filed July 13, 1886. Serial No. 207,895. (No model.)

To all whom it may concern:

Be it known that I, FRIEDRICH TWICK, of Sheboygan, in the county of Sheboygan and State of Wisconsin, have invented a new and 5 useful Improvement in Combined Land-Roller and Clod-Crusher, of which the following is a full, clear, and exact description.

Reference is to be had to the accompanying drawings, forming a part of this specification, 10 in which similar letters of reference indicate corresponding parts in all the figures.

Figure 1 is a plan view of my combined land-roller and clod-crusher, parts being broken away. Fig. 2 shows the inner side of one of 15 the side bars of the frame. Fig. 3 is a sectional side elevation of the machine. Fig. 4 is a longitudinal section of a colter-shaft and a cross-section of the shaft-bearings. Fig. 5 is a rear elevation of a central section and 20 showing a part of the main frame. Fig. 6 is a sectional elevation of one of the colters. Fig. 7 is a sectional elevation of the mechanism for connecting a wheel with the main frame.

The object of this invention is to improve the 25 construction of the combined land-rollers and clod-crushers for which Letters Patent No. 339,601 were issued to me April 6, 1886, in such a manner as to make them more convenient in use and more reliable in operation.

30 The invention consists in the construction and combination of various parts of the machine, as will be hereinafter fully described, and then pointed out in the claims.

A represents the main frame of the machine, 35 to the centers of the cross-bars of which is attached the tongue B. The side bars, C, of the frame A are made of iron, have their middle parts curved downward, and have flanges D at their ends, to receive the ends of the cross-bars of the said frame, and flanges E at their centers, to receive the mechanism for connecting the wheels and the colter-shafts with the main frame, as will be hereinafter described.

To the centers of the side bars, C, of the 45 frame A are attached bolts F, to which are pivoted, at their angles, the elbow-levers G. To the short arms of the elbow-levers G are attached the axles H of the wheels I, that carry the machine. The other arms of the elbow-levers G are made long, or have handles attached to them, so that they can be readily 50 operated. With this construction, when the

short arms of the elbow-levers G are in a horizontal position and the long arms vertical, the frame A and its attachments will be lowered, and the machine will rest and be carried upon the colters, hereinafter described. When the long arms of the elbow-levers G are swung down into a horizontal position, the short arms of the said levers will be swung down 55 into a vertical position, the frame A and its attachments will be raised, raising the colters from the ground, and the machine will rest and be carried upon the wheels I. The outer ends of the long arms of the elbow-levers G, 60 when in a horizontal position, rest in keepers J, attached to the frame A, and are secured in the said keepers by pins K, passed through them above the said ends.

L are circular colters, the sides of the faces 70 of which are beveled upon a curve to form tapered edges, as shown in Figs. 1, 5, and 6. The colters L may be of any desired diameter from twelve to twenty-eight inches, are preferably cast hollow, (see Fig. 6,) and are placed side 75 by side upon two shafts, M, where they are secured in place by washers N and set-screws O, as shown in Figs. 1 and 5. The two shafts 80 M are placed parallel with each other, and their ends are secured to the under sides of the side bars, C, of the frame A by bearings P, bolted to flanges upon the said side bars in such positions that the edges of the colters of the one shaft will be in the spaces between the edges of the colters of the other shaft, as shown 85 in Fig. 1. The shafts M are tubular, have their ends closed by plugs Q or caps, and have holes R in the sides, near their ends, connecting with annular grooves in the inner surfaces of the bearings P, so that oil poured into oil-cups S 90 on the upper parts of the said bearings will flow into the interiors of the said shafts.

In the shafts M, within the hubs of the colters L, are formed holes T, through which oil can escape to lubricate the bearings of the said 95 colters.

To the front and rear cross-bars, both or either, of the frame A are attached bars U, in the adjacent sides of which are formed vertical grooves V, to receive ribs W, formed upon the outer sides of the side bars of the vertical frames X, so that the said frames can be moved 100 up and down vertically.

To the lower ends of the side bars of the

frames X are attached perforated tubular shafts Y, provided with colters Z, secured in place by washers a and set-screws b, as hereinbefore described with reference to the shafts M and 5 colters L.

To supports c, attached to the centers of the top bars of the frames X, are pivoted the ends 10 of levers d, which are fulcrumed to standards e, attached to the tongue B. The inner ends of the levers d engage with catch-bars f, attached to the frame A, so that the said levers will be held securely in place when adjusted to raise the frames X and colters Z away from the ground.

15 g is the driver's seat, the standard h of which is attached to the tongue B.

i are scrapers, the engaging ends of which are so formed as to fit into the spaces between the beveled edges of the colters, and thus, 20 move any soil that may have lodged in the said spaces. The shanks of the scrapers i are attached to cross-bars j. The forward cross-bar j is secured to the bars k, attached to the frame A by bolts l, which pass through short 25 slots in the said bars k, so that the said cross-bar j and its scrapers can be moved forward or back to adjust the engaging ends of the said scrapers at any desired closeness to the colters L. To the rear cross-bar j are attached the 30 forward ends of the plates m, the rear ends of which are secured to the rear cross-bar of the frame A by bolts n. The rear ends of the plates m are slotted to receive the bolts n, so that the rear cross-bar j can be moved forward 35 or back to adjust the engaging ends of its scrapers to any desired closeness to the colters.

Having thus fully described my invention, I claim as new and desire to secure by Letters Patent—

40 1. In a combined land - roller and clod-crusher, the combination, with the middle part of the end of the frame A, of the bars U, having vertical grooves V, the sliding frame X, carrying a series of beveled-edged colters, 45 and having tongues W engaging with the

grooves of the said bars U, and the lever d, connected with the said sliding frame X, and fulcrumed to standards attached to the said frame A, substantially as herein shown and described, whereby the said colters can be 50 readily raised and lowered, as set forth.

2. In a combined land - roller and clod-crusher, the combination, with the frame A and the colters L, having beveled edges, of the tubular shafts M, having their ends closed 55 and provided with inlet oil-holes R, connecting with oil-holes in the shaft-bearings, and having outlet oil-holes T within the hubs of the said colters, substantially as herein shown and described, whereby the colter-bearings can be 60 readily oiled, as set forth.

3. In a combined land - roller and clod-crusher, the combination, with the frame and a series of colters having beveled edges, of a cross-bar adjustably secured to the said frame, 65 and scrapers secured to said bar, whereby provision is made for adjusting the said scrapers to or from the colters, substantially as herein shown and described.

4. In a combined land - roller and clod-crusher, the combination, with the frame A and the forward series of colters, L, having beveled edges, of the scrapers i, the cross-bar j, carrying the said scrapers, the slotted bars k, attached to the frame A, and the connecting-bolts l, substantially as herein shown and described, whereby the spaces between the 75 said edges will be kept clear of soil, as set forth.

5. In a combined land - roller and clod-crusher, the combination, with the frame A 80 and the wheels I, of the side bars, C, provided with the flanges D E and the pivot-bolts F, the elbow-levers G, pivoted to the said bolts, and the axles H, attached to the lower ends of the said elbow-levers, substantially as herein 85 shown and described.

FRIEDRICH TWICK.
